ARTHUR R. WHITEHORN, OF ROCHESTER, NEW YORK, ASSIGNOR TO GENERAL RAILWAY SIGNAL COMPANY, OF ROCHESTER, NEW YORK

CENTRALIZED TRAFFIC CONTROL SYSTEM FOR RAILROADS

Application filed June 13, 1930. Serial No. 460,929.

This invention relates to centralized traffic controlling systems for railroads, and more particularly to the provision of means for controlling a switch machine and four signals at a diverging route location over a single circuit and without the employment of selector apparatus.

In accordance with the present invention it is proposed to control apparatus to five different conditions over the same line circuit by employing current of one or another polarity and in modulating or not modulating such current, thereby obtaining currents of four different characteristics, the fifth being obtained by opening the line circuit under consideration.

Other objects, purposes and characteristic features of the present invention will in part be pointed out hereinafter and in part be obvious from the accompanying drawing.

In describing the invention in detail reference may be had to the accompanying drawing in which:—

Fig. 1 illustrates the central office equipment within a dotted rectangle and conventionally shows the apparatus at a distant diverging route location, and

Fig. 2 shows a modified arrangement for supplying current to the neutral relays.

Structure.—Referring to the drawing, the dotted rectangle T denotes a central office or tower, and the rails of the main track have been designated by the reference character 10, and those of a passing siding or the diverging route are designated by the reference number 11. These track rails are divided by insulating joints 12 in the usual way to provide the usual main track circuits and detector track circuits. The side track 11 is connected to the main track 10 by a track switch S, which track switch is operated by a switch machine SM. The east bound starting signal 2, the east bound dwarf signal 2^a, the west bound main signal 1 and the take-siding signal 1^a, as well as the switch machine SM, are controlled from the distant tower T through the medium of the polar-neutral control relay Z and the neutral relays Z¹ and Z². These relays Z, Z¹ and Z² are controlled from the battery B at the central office T through

the medium of the interrupter I and the levers NRL and DL. Having now made brief references to each of the elements of the system illustrated conventionally, it is believed expedient to consider the operation of the system to get a better understanding of the inter-relation of these devices and the functions intended to be carried out thereby.

Operation.—Let us assume that there is a west bound train approaching on the main track, and that the operator wishes to clear the signal 1^a to permit this train to pass into the diverging route or side track. It is of course necessary to operate the track switch S to the take-siding position, and this may be accomplished by operating the normal-reverse lever NRL to the left hand position, and since the signal to be cleared is a west bound signal the operator will move the direction lever DL to its left hand position. With the levers NRL and DL in their left hand position the following circuit for the control relay Z is closed:—beginning at the mid-point of the battery B (this being the positive terminal of the left hand portion of the battery B), wire 15, common return wire C, wire 16, primary winding of the relay Z, wire 17, lever DL, wires 18 and 19, lever NRL, wire 20, to the negative terminal of the battery B. The closure of this circuit operates the relay Z to its left hand position, thereby connecting the relay Z¹ in a circuit including the secondary winding of the relay Z, and the wires 6, 7, 8 and 9, but since the current applied to the circuit is a steady uni-directional current no current is induced in the secondary winding of the relay Z, and the relay Z¹ remains deenergized. Further, with the relay Z energized toward the left, the switch machine SM is operated to the take-siding position by the application of a potential to the reverse wire R through the medium of contacts 40 and 38 of the relay Z. With the relay energized to the left and the relay Z¹ deenergized the following circuit for the signal 1^a is closed:—beginning at the terminal B of a suitable battery or other current source, front contact 22 of the relay Z, wire 23, polar contact 24 of the relay Z assuming its left hand position, wire 25, back contact 26 of the

relay Z^1 , wire 27, mechanism of the signal 1^d, through suitable contacts controlled in accordance with traffic conditions in advance, and to the other terminal of the battery containing the terminal B. The train in question may therefore accept the signal 1^d if traffic conditions in advance are favorable and may pass into the diverging route.

Had the operator desired to have the train in question continue on the main track, he would have operated the lever NRL to the right and the lever DL to the left, thereby closing the same circuit heretofore traced, with the exception of including the right hand part of the battery B instead of the left hand half. Under this condition the relay Z would have been energized by current of the opposite polarity and would have been operated to the right, but the relay Z^2 would have remained deenergized, because the current flowing in the circuit under consideration, namely the circuit including wires 9, 8, 46 and 47, would have been a steady direction current. Under these conditions of the relay Z and Z^2 the signal 1 would have been cleared, assuming favorable traffic conditions exist ahead, through the following circuit:—beginning at the terminal B, front contact 22 of the relay Z, wire 28, polar contact 24, wire 28, back contact 29 of the relay Z^2 , wire 30, through the mechanism of signal 1 and through suitable contacts (not shown) controlled in accordance with traffic conditions ahead.

Let us now assume that there is an east bound train on the main track and to the rear of signal 2, and that the operator wishes this train to proceed on the main track. In order to do this the operator must clear the signal 2, and this may be accomplished by moving the lever NRL to its right hand dotted position and by moving the direction lever DL to its right hand dotted position. With these levers NRL and DL assuming the right hand position, the following circuit for the control relay Z is closed:—beginning at the positive terminal of the terminal B, wire 32, lever NRL, wires 19 and 33, winding of the interrupter I, normally closed contact 34 of the interrupter I, wire 35, lever DL, wire 17, primary winding of the relay Z, wires 16, C and 15, and back to the mid-point of the battery B. The closure of the circuit just traced allows current of positive polarity to flow through the primary winding of the relay Z, but since this current flows through the interrupter I it will be intermittently interrupted, thereby causing a pulsating current of positive polarity to flow through the circuit just traced. This pulsating current of positive polarity operates the polar contacts 37, 38 and 24 to the right hand position and effects closure of the neutral contacts 39, 40 and 22, and since the pulsating current pulsates the flux in the core of the relay Z a current is induced in the secondary winding 41

of this relay Z, which current will flow through the winding of the relay Z^2 and operate its contact 29 to its attracted position. Under this condition of the relays Z and Z^2 the starting signal 2 may under favorable traffic conditions ahead be operated to a proceed position through the following circuit:—beginning at the terminal B, front contact 22 of the relay Z, wire 23, polar contact 24 assuming its right hand position, wire 28, front contact 29 of the relay Z^2 , wire 43, mechanism of the signal 2, through suitable contacts controlled in accordance with traffic conditions in advance of the signal 2.

It is of course understood that the control relay Z does not only constitute a relay, but also constitutes a transformer in that it includes two windings linking the core structure of the relay, so that if a pulsating current is applied to the main winding of the relay Z a potential is induced in the secondary winding 41 of this relay, and this alternating current potential may flow through the relay Z_1 or relay Z_2 , depending on the polarity of the pulsating current applied to the relay Z.

Let us now assume that there is an east bound train standing on the diverging route of side track 11, and that the operator wishes this train to proceed in an eastwardly direction on to the main track 10. This may be accomplished by moving the lever NRL to the left hand or reverse position, and moving the direction lever DL in its right hand or east bound position. With these levers in the last mentioned position, pulsating current of negative polarity is applied to the control relay Z, through the last traced circuit for this relay Z (said circuit including the interrupter I), thereby causing the relay Z to be energized to its left hand position and permitting the voltage induced in the secondary winding 41 of relay Z to cause alternating current to flow in the winding of the relay Z^1 . Under these conditions of the relays Z and Z^1 , the signal 2^d is permitted to clear, assuming clear traffic conditions exist ahead of the signal 2^d, through the following circuit:—beginning at the terminal B, front contact 22 of relay Z, wire 23, polar contact 24 to the left, wire 25, front contact 26 of the relay Z^1 , wire 45, mechanism of the signal 2^d, and suitable relay contacts controlled in accordance with traffic conditions ahead.

It is of course understood that the invention is equally as well applicable to light signals as to the semaphore signals illustrated. Also, if desired, a separate transformer may be used instead of using the relay Z as a transformer. An arrangement of this kind has been shown in Fig. 2, where the transformer TR has its primary winding included in series with the relay Z^2 and has its secondary winding connected in exactly the same way as the secondary winding 41 in Fig. 1, as is

evident from the fact that like wires and contacts have been designated by like reference characters having distinctive exponents one.

The apparatus of Fig. 1 has been shown in its normal condition, in which all of the signals are held at stop and the switch machine assumes its last operated position, namely the main track position. The interrupter I is of the usual construction, including the normally closed biased contact, which contact comprises a tuned armature, and which contact is opened upon the flow of current in the winding of the interrupter this opening of its contacts of course interrupts the flow of current allowing the contact to reclose, this operation is repeated in rapid sequence, so that, a pulsating current of a frequency corresponding to the tuning of the armature of the interrupter flows.

Having thus shown and described two specific embodiments of the present inventions, it is desired to be understood that the particular embodiments selected have been selected for the purpose of exemplifying the invention, rather than illustrating its scope, or the exact construction preferably used in practicing the invention, and that various changes, modifications and additions may be made to the arrangement illustrated without departing from the spirit of the invention or its scope, except as demanded by the scope of the appended claims.

What I claim as new is:—

1. In combination, a line circuit, a double winding relay having one of its windings included in said line circuit, a second relay included in circuit with the other winding of said double winding relay, and means for energizing said line circuit with either continuous or pulsating unidirectional current.

2. In combination, a line circuit, a double winding polar relay having one of its windings included in said line circuit, a second relay included in circuit with the other winding of said double winding relay, and means for energizing said line circuit with continuous current of one polarity or the other or pulsating uni-directional current of one polarity or the other.

3. In combination, a line circuit, a double winding polar relay having one of its windings included in said line circuit, a second relay included in circuit with the other winding of said double winding relay, and means for including a battery of one polarity or the other in said circuit and including an interrupter in said circuit.

4. In combination, a line circuit, a double winding relay having one of its windings included in said line circuit, a second relay included in circuit with the other winding of said double winding relay, a contact of said double winding relay included in the circuit of said second relay, and means for energizing

ing said line circuit by direct current or by pulsating current.

5. In combination, a line circuit, a double winding polar relay having one of its windings included in said line circuit, a second relay included in circuit with the other winding of said double winding relay, a polar contact of said double winding relay included in the circuit of said second relay, and means for energizing said line circuit by direct current of one or the other polarity or by pulsating current of a particular polarity.

6. In combination, a line circuit, a double winding polar relay having one of its windings included in said line circuit, a second relay included in circuit with the other winding of said double winding relay, means for energizing said line circuit with continuous current of one polarity or the other or pulsating uni-directional current of one polarity or the other, a track switch of a railway system, a signal for governing the movement of traffic on the main track and on the diverging route for each direction of train movement, and circuits for governing said signals in accordance with the direction a train shall move controlled by said second relay and for governing said signals to indicate whether such train shall move on the main track or on the diverging route controlled by said polar relay.

7. In combination, a line circuit, a double winding polar relay having one of its windings included in said line circuit, a second relay included in circuit with the other winding of said double winding relay, means for energizing said line circuit with continuous current of one polarity or the other or pulsating uni-directional current of one polarity or the other, a track switch at a diverging route point, a switch machine for operating said track switch, means for controlling said track switch by said polar relay, and means for controlling the direction indication of said signals in accordance with the position of said second relay.

8. In combination, a line circuit, a polar relay included in said line circuit, a second relay inductively coupled to said line circuit, means for energizing said line circuit with continuous current of one polarity or the other or pulsating uni-directional current of one polarity or the other, and railway traffic controlling apparatus controlled by said relays.

9. In combination, a line circuit, a polar relay having its winding included in said line circuit, a second relay inductively coupled to said line circuit, and means for including a battery of one polarity or the other in said circuit and including an interrupter in said circuit.

10. In combination, a line circuit, a relay having its winding included in said line circuit, a second relay inductively coupled with

said line circuit, a contact of said first relay included in the circuit of said second relay, and means for energizing said line circuit by continuous direct current or by pulsating current.

11. In combination, a line circuit, a polar relay having its winding included in said line circuit, a second relay inductively coupled with said line circuit, a polar contact of said first relay included in the circuit of said second relay, and means for energizing said line circuit by direct current of one or the other polarity or by pulsating current of a particular polarity.

12. In combination, a line circuit, a polar relay having its winding included in said line circuit, a second relay inductively coupled to said line circuit, means for energizing said line circuit with continuous current of one polarity or the other or pulsating uni-directional current of one polarity or the other, a track switch of a railway system, a signal for governing the movement of traffic on the main track and on the diverging route for each direction of train movement, and circuits for governing said signals in accordance with the direction a train shall move controlled by said second relay and for governing said signals to indicate whether such train shall move on the main track or on the diverging route controlled by said polar relay.

13. In combination, a line circuit, a polar relay having its winding included in said line circuit, a second relay inductively coupled to said line circuit, means for energizing said line circuit with continuous current of one polarity or the other or pulsating uni-directional current of one polarity or the other, a track switch at a diverging route point, a switch machine for operating said track switch, means for controlling said track switch by said polar relay, and means for controlling the direction indication of said signals in accordance with the position of said second relay.

In testimony whereof I affix my signature.
ARTHUR R. WHITEHORN.
